By Wm. O'Brien, Atty.

UNITED STATES PATENT OFFICE.

FRANK W. CARLSON, OF CHICAGO, ILLINOIS.

FLOOR-DRAIN VALVE.

Application filed July 25, 1927. Serial No. 208,239.

This invention relates to floor drain valves and it has for its object to provide a simple, durable and dependable valve which will not leak and permit back water or sewer gas to pass therethrough and which can be quickly operated to open or close the valve and easily disassembled without removing the casing or body of the valve to permit access to the sewer for cleaning or other purposes.

10 Floor drain valves are usually set nowadays in cement floors on one end of a sewer pipe and provided with a water seal against sewer gas from passing through the valve. If the valve is left open for a sufficient time 15 the natural evaporation of the water, is not replenished, will break the seal and allow sewer gas to flow into the building. There are floor drain valves in use which are provided with movable means to open and close 20 the valve, but they are difficult to operate, they easily become stuck and inoperative, in some cases the movable means is not readily observable or accessible and it is my observation, generally speaking, that they are inefficient for the purpose intended because they 25 will not prevent the escape of sewer gas when the water seal is destroyed even when the movable parts of the drain valve are closed.

My invention also has for its object to provide an efficient closure for a floor drain valve which will prevent the escape of sewer gas therethrough if the water seal in the sewer pipe is destroyed by evaporation or otherwise.

30 And a further object of the invention is to provide a floor drain valve with operable parts of simple construction which can be easily operated for opening and closing the valve as desired.

35 In the accompanying drawings illustrating a selected embodiment of my invention: Fig. 1 is a top plan view of the floor drain valve with the bar strainer top partly broken away.

40 Fig. 2 is a transverse sectional view on the line 2—2 of Fig. 1, showing the valve parts in closed position.

Fig. 3 is a transverse sectional view on the line 3—3 of Fig. 1.

45 Fig. 4 is a horizontal sectional view on the line 4—4 of Fig. 2.

Fig. 5 is a detail sectional view.

Referring to the drawings 6 is the casing or body of the valve having a reduced end 7

to engage a sewer pipe and a peripheral 55 flange 8 to be seated substantially flush with a basement floor. An inner closure plate 9 is seated upon a peripheral shoulder 10 and is removably fastened thereto by screws 11. The inner plate 9 is provided with a notch 12 to engage a lug 13 on the casing for registering the inner plate in proper position in the casing, so that the screws 11 may be readily engaged with the holes provided for them in the casing. The inner plate has a depending and transversely disposed comparatively narrow trough-like portion 14 which forms a chamber 15.

50 A plurality of seats 16 are arranged in parallel relation across the chamber 15 in the top of the inner plate to receive elongated cores 17 which are provided with a plurality of transverse passages 18. An outer clamping plate 19 is removably fastened to the inner plate 9 by screws 20 and it is provided 55 on its bottom with seats 21 to receive the cores 17. The outer plate is provided with a notch 20' to register with the lug 13 so that the outer plate will be properly positioned with respect to the inner plate. The seats 16 and 60 21 are relatively shallow, the cores 17 fits snugly therein and space the outer and inner plates apart. The inner plate has openings 22 and the outer plate has openings 23 to register with the transverse passages 18 in 65 the cores. Arms 24 are rigidly secured to the cores and project downward therefrom in parallel relation and are engaged at their lower ends with a transverse link 25. The arm of one core, preferably the middle core, 70 as shown, projects upward through an opening 26 in the upper member and forms a lever arm 27. A removable top 28 is adapted to be seated in the upper end of the casing and upon the outer plate 18 and it is provided 75 with a plurality of alternate bars 29 and slots 30. A hole 31 is provided in the peripheral portion of the cap to be engaged with the lever arm 27 to provide a convenient means for operating the lever if desired.

80 My invention provides a floor drain valve of simple and efficient construction which can be easily installed, the movable parts of which can be easily assembled and disassembled, and which can be readily operated for opening and closing the valve as desired. The cores are made of round bars transversely bored to provide the round passages 18

which are spaced apart and do not materially weaken the cores. These cores operate snugly in the seats in the inner and outer plates, but I pack the space 32 between the 5 plates with heavy grease to form an effective seal for the valve and to facilitate the operation of the movable parts.

The use of this grease makes it unnecessary to machine finish any of the parts except possibly the seats and cores. I prefer to make the casing and top of cast iron, the inner and outer plates of brass castings and the cores and arms of brass bars. The plate may be secured as tightly as desired to the inner 10 plate by means of the screws 20 to form an efficient closure through the cores, but this adjustment should always be such as to permit the cores to be operated when required after opening and closing the valve.

Changes in the form, construction and arrangement of parts may be made without departing from the spirit and without sacrificing any of the advantages thereof and I reserve the right to make all such changes as 15 fairly fall within the scope of the following claims.

I claim:

1. A floor drain valve comprising a casing, an inner plate secured to the casing and 20 having a plurality of parallel seats therein, said seats having openings through the plate, a plurality of cores arranged in said seats and having passages to register with the openings in the plate, and means for operating 25 said cores.

2. A floor drain valve comprising a casing, an inner plate secured to the casing and having a plurality of parallel elongated seats 30 therein, said seats having openings through the plate, a plurality of round bar cores arranged in said seats and having transverse 35 passages to register with the openings in the plate, and means for operating said cores.

3. A floor drain valve comprising a casing, an inner plate secured to the casing and having a plurality of parallel seats therein, an outer plate having a plurality of seats therein, the seats in the outer plate being disposed 40 opposite the seats in the inner plate and all of said seats having openings through the respective plates, a plurality of cores arranged 45 between the plates in said seats and having passages to register with the openings in the plates, and means for operating said cores.

4. A floor drain valve comprising a casing, an inner plate secured to the casing and having a plurality of parallel seats therein, an outer plate having a plurality of parallel 50 seats therein, the seats in the outer plate being disposed opposite the seats in the inner plate and all of said seats having openings extending through the respective plates, means for detachably securing the outer plate to the inner plate, a plurality of cores arranged in 55 said seat and having passages to register with

the openings in the plates, and means for operating said cores.

5. A floor drain valve comprising a casing, an inner plate secured to the casing and having a plurality of elongated parallel seats 70 therein, an outer plate removably secured to the inner plate and having a plurality of seats therein disposed opposite the seats in the inner plate, the seats in the outer plate having openings which register with openings in the 75 seats in the inner plate, a plurality of round bar cores arranged in said seats and having passages to register with the openings in the plates, and means for operating said cores.

6. A floor drain valve comprising a casing, an inner plate secured to the casing and having a transversely extending trough-like portion forming a chamber, a plurality of parallel seats in the plate, said seats having 80 openings through the plate, a plurality of cores arranged in said seats and having passages 85 to register with said openings, and means arranged in said chamber for operating said cores.

7. A floor drain valve comprising a casing, an inner plate secured to the casing and having a transversely extending trough-like portion forming a chamber, a plurality of parallel seats in the plate, said seats having 90 openings through the plate, a plurality of cores arranged in said seats and having passages 95 to register with said openings, and means in said chamber connecting the cores for simultaneous operation.

8. A floor drain valve comprising a casing, an inner plate secured to the casing and having a transversely extending trough-like portion forming a chamber, a plurality of parallel seats in the plate, said seats having 100 openings through the plate, a plurality of cores arranged in said seats and having passages 105 to register with said openings, and means in the chamber connecting the cores for simultaneous operation and comprising arms rigid with the cores and a link connecting the arm. 110

9. A floor drain valve comprising a casing, an inner plate secured to the casing and having a transversely extending trough-like portion forming a chamber, a plurality of parallel seats in the plate, said seats having 115 openings through the plate, a plurality of cores arranged in said seats and having passages to register with said openings, means in the chamber connecting the cores for simultaneous operation and a lever projecting above 120 one of the cores and rigid therewith for operating said means and cores.

10. A floor drain valve comprising a casing, an inner plate secured to the casing and having a transversely extending trough-like portion forming a chamber, a plurality of parallel seats in the plate, said seats having 125 openings through the plate, a plurality of cores arranged in said seats and having 130 passages to register with said openings, and

means for operating the cores simultaneously comprising arms rigid with the cores and projecting into said chamber, a link connecting the inner ends of the arms, and a lever 5 engaged with one of the cores for operating said means and cores.

11. A floor drain valve comprising a cas-

ing, a movable valve member mounted in the casing, a lever arm for operating said valve member, and a skeleton top having an opening arranged to be engaged with said lever arm. 10

FRANK W. CARLSON.
